PRINTING TRANSFERRING MACHINE

Albert W. Mills, Endicott, N. Y., assignor to International Business Machines Corporation, New York, N. Y., a corporation of New York

Application May 8, 1941, Serial No. 392,409

14 Claims. (CL 101—134.5)

This invention relates to a transfer machine and more particularly to a machine for posting ledger sheets by the process of preparing a negative record on the back of the original record, moistening the front of the original with a suitable solvent, and pressing the back of the original against the face of the ledger sheet.

A particular object of the invention is to provide improved feeding and aligning devices for the record sheets employed in such machine.

A further object is to provide means for effecting automatic and periodic alignment of the original sheet to insure accurate registration of the postings on the ledger sheets.

A further object of the invention is to provide mechanism for controlling the feeding of the original sheet so that multiple posting from a single line may be effected.

A still further object resides in the provision of novel mechanism cooperating with the posting devices for indicating for each line of the original sheet whether or not posting has been effected from the line and how many times such posting has taken place.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a top plan view of the machine.

Fig. 2 is a sectional elevation taken on lines 2—2 of Fig. 1.

Fig. 3 is a section taken on lines 3—3 of Fig. 2.

Fig. 4 is an enlarged detail view of the posting mechanism and the sheet feeding devices.

Fig. 5 is a view similar to Fig. 4 with the parts in operated position.

Figs. 6 and 7 are details of the pressure bar equalizing device.

Fig. 8 is a detail view of the clutch and clutch release mechanism.

Fig. 9 is a detail of the operating mechanism for operating the ledger sheet clamps.

Fig. 10 is a detail of the control device for automatically releasing the pressure feed rollers of the original sheet feeding mechanism.

Fig. 11 is a detail of parts of the auxiliary feed and aligning mechanism.

Fig. 12 is a detail of further parts of the feed roller release mechanism.

Fig. 13 is a detail of the operating mechanism for the ledger sheet carriage.

Fig. 14 is a detail of the line space and repeat key mechanism.

Fig. 15 is a detail of the release key locking mechanism.

5 Fig. 16 is a detail of the ribbon operating mechanism.

Fig. 17 is a detail of the indexing finger operating mechanism.

10 Figs. 18 and 19 are details of the marking device.

Fig. 20 is a view showing the aligning devices for the ledger sheet.

Fig. 21 is a detail view taken on lines 21—21 of Fig. 20.

15 Fig. 22 is an enlarged view of parts shown in Fig. 1.

Figs. 23 and 24 are details of a special posting elimination shield.

The original paper from which the copy is to 20 be taken is printed in a conventional manner on a tabulator, typewriter or other suitable medium and is backed with suitable carbon paper while being printed. The original may take the form of single sheets, fanfold or continuous roll.

25 The transfer is accomplished by interposing a ribbon or similar medium moistened with solvent above the area to be transferred and then applying pressure on the ribbon to bring the ribbon, the original and the ledger sheet or receiving 30 paper together. The solvent dissolves a portion of the carbon from the original and deposits it on the ledger sheet.

The machine in its general operation is substantially the same as that disclosed in my Patent 35 No. 2,189,043, granted February 6, 1940. The general operation will, therefore, be but briefly described with the improvements of the present invention more particularly explained.

The machine includes a table or plate 21 (Fig. 40 1) supported between side frames 22 and 23. Upon this table is placed the ledger sheet to receive the impression. The frames 22 and 23 are rigidly joined by a lower pressure bar 24 (Fig. 2), bars 25 and 26 and a motor support 45 plate 27.

A motor 28 (Fig. 3) provided to drive the several mechanisms of the machine is mounted on the plate 27. The motor, through a pulley and belt connection 29 and a gear box 30 supported 50 on the plate 27 operates a short shaft 31 supported in bracket 32 and secured to the plate 27. A clutch disk 34 (see also Fig. 8) fast on the shaft 31 is provided with notches 35 about its periphery, with which notches a clutch pawl 36 pivotally carried by a clutch arm 37 fast on a cam

shaft 38 cooperates. The cam shaft 38 is supported in brackets 39 secured to the plate 27, the shafts 31 and 38 being in axial alignment.

The arm 37 (Fig. 8) and shaft 38 are normally held against rotation by an arm 40 fast on a stud 41 supported by the bracket 32 (see Fig. 3). The arm 40 has a shoulder 42 which normally lies in the path of the arm 37 and of a tail of the pawl 36, thus holding the pawl 36 out of engagement with the disk 34. A stud 43 on the arm 40 fast on the stud 41 projects through a slot 45 in a link 46 whose right hand end is supported by a spring 46a. The other end of the link is connected to an arm 47 fast on a shaft 48 journaled in the frames 22 and 23. Also fast on the shaft 48 is a release bar 49, located near the end of the shaft and being arranged to lie conveniently on one side of the table 21 (see Fig. 1).

In order to initiate an operation of the machine, the operator depresses the bar 49, which movement rocks the shaft 48 and arm 47 counterclockwise thrusting the link 46 toward the right. At this movement, the left edge of notch 45 engaging the stud 43 rocks the arm therewith, removing the shoulder 42 from engagement with the arm 37 and the tail of the pawl 36. The pawl, thus freed, is engaged with one of the notches 35 by a spring 56. The arm 37 and the shaft 38 make one complete counterclockwise rotation.

A cam 57 fast on the shaft 38 adjacent the extension 50 of link 56 has a single notch in its periphery cooperating with a roller 58 on the extension 50. As soon as the shaft 38 starts to rotate, the cam 57 rocks the extension 50 clockwise freeing the arm 40 to be acted upon by a spring 59 which immediately restores the arm to its normal position. Near the end of the rotation of shaft 38, the shoulder 42 reengages and rocks the pawl 36 out of engagement with the disk 34 and stops the arm 37 and shaft 38. A spring pressed retaining pawl 60 prevents retrograde movement or rebound of the arm 37.

If the operator has released the bar 49 before the end of the rotation of shaft 38, the parts assume their normal positions when the notch in cam 57 comes opposite the roller 58. However, if the bar 49 is held depressed, holding the link 46 in its moved position, that is, toward the right, then when the cam 57 releases the roller 58, the pin 43 will rest on top of the link 46 and it will be necessary for the operator to release the bar 49, permitting a spring 61 (Fig. 8) having one end attached to an arm 62 fast on the shaft 48 to restore the link toward the left before another operation may be initiated.

Ledger carriage

The ledger sheet indicated at 63 (Figs. 1, 4, 5, and 20) on to which the transfer is to be made is placed on the table 21, with the first line (in the case of a new sheet) or the next blank line on which a copy is to be made beneath a transparent line finder 64 adjustably mounted on a bar 55 supported in a manner to be described. This finder has parallel lines scribed thereon to assist the operator in the proper positioning of the ledger sheet. The sheet is located on the table 21 with its left edge beneath spring pressed clamps 65 (Figs. 1, 2, 9, and 13), there being four clamps 65 mounted on the ledger carriage.

The ledger carriage includes a bar 66 (Figs. 3, 9, 13, and 15) integral with a pair of spaced blocks 67 slidably mounted on rods 68 which are

supported in brackets 69 secured to and extending inwardly from the left side frame 22. Referring to Fig. 15, it can be seen that a surface of the bar 66 is in the same plane as the top of the table 21. A stop edge 70 (Fig. 13) of the bar 66 locates the edge of the ledger when it is placed in position on the table (Fig. 20). The clamps 65 are slideable vertically in the bar 66 and are normally urged downwardly to grip the paper 63 by blade springs 71 secured to the under side of the bar 66.

After the ledger sheet is in proper position, the operator depresses the release bar 49 whereupon the shaft 38 rotates. Shortly thereafter, a cam 72 (Fig. 9) permits a spring 73 to rock clockwise an arm 74 mounted on a shaft 75 supported in the brackets 39 (Fig. 3). An arm 76 fast to a shaft 77 (Figs. 3 and 9) is connected by a link 78 to the arm 74. Also fast on the shaft 77 is a bell crank 79 whose downwardly extending arm is connected by a link 80 to a bell crank 81 pivoted on a stud projecting from a fixed bracket. A bar 82 supported on the bell cranks 79 and 81 is normally pressed upwardly against the paper clamps 65 and against the tension of springs 71 by the cam 72.

The clockwise movement of the arm 74 described above is transmitted by the link 78 to rock the arm 76, shaft 77, bell crank 79 and due to the connection 80 the bell crank 81 counterclockwise to lower the bar 82. This permits the springs 71 to draw the clamps 65 down gripping the ledger sheet 63 firmly between said clamps and the carriage bar 66.

Shortly after the ledger sheet is gripped in the manner just described, mechanism now to be described is operated to shift the carriage a distance sufficient to move the selected line from its position beneath the line finder (Figs. 4 and 20) to a position under a pressure bar 83. This mechanism includes a pair of cams 84 (Figs. 3 and 13) cooperating with a bell crank 85 pivoted on the shaft 75 and which is connected by a link 86 to an arm 87 fast to a shaft 88 supported between the side frames 22 and 23. Another arm 89 also fast on the shaft 88 carries at its free end a pin 90 extending between spring connected arms 91 which also cooperate with the pin 90 in an arm 90. The arm 90 is connected by a link 96 to the rear block 67 of the ledger carriage. The spring 97 between arms 91 serves as a safety coupling between arm 89 which is secured on shaft 88 and arm 90 which is free on the shaft, the rocking of arm 90 in either direction being through spring 97.

As the shaft 38 rotates, the bell crank 85 is rocked clockwise, which movement through the link 86 rocks the arm 87, shaft 88 and arm 89 in the same direction. This movement through the link 96 draws the carriage toward the right (Figs. 2 and 13) and toward the rear of the machine for the purpose set forth above.

In order to align the typed matter on the original sheet with the proper column on the ledger sheet, there is provided a plurality of index fingers 51 (Figs. 2, 4, and 20) each attached to a gripping shield 51a (Fig. 1), slidably mounted on a rod 52 supported for oscillation between the frames 22 and 23. The ledger sheet 63 (Fig. 20) is placed in position on the table 21 and manually shifted to position beneath the pressure bar 83, at which point it is directly under the fingers 51. The fingers are now adjusted along the rod 52 to bring the fingers in line with the limits between which it is desired to have the

transfer appear as indicated in Fig. 20. With the fingers 51 in their selected positions, the original sheet is inserted and the first line of typed matter is positioned with the top of the typed matter aligned with the bottoms of the fingers 51 and the first and last characters in line with the notches in the left hand and right hand fingers 51 respectively. The arms 164 (Fig. 4) are now operated to bring the rolls 139 into contact with the roll 137, thus holding the original sheet 153 in position.

The bar 55 which supports the line finder 64 (Fig. 20) is adjustably supported in slots in the side members or plates 101 and 102 (Fig. 1) of the moisture reservoir, to permit adjustment of said bar and the line finder 64 toward and away from the index fingers 51. The purpose of this adjustment is to vary the line spacing on the ledger sheet 63. It will be remembered that the ledger sheet receives an invariable movement from line finding position to transfer position. Obviously, if the line finder 64 is adjusted closer to the transfer position, the spacing of the lines transferred to the ledger sheet will be increased, and if the line finder is adjusted farther from the transfer position, the line spaces on the ledger sheet will be decreased.

Referring to Figs. 4 and 20, the line finder 64 is supported in a frame 228 which is slidable along bar 55 and may be adjusted slightly in the direction of sheet feeding by screws 229 which are collared to straddle the bar. By turning the screws, relative movement is obtained between the frame 228 and bar 55 so that the scribed lines 230 may be accurately adjusted. The frame 228 also has two pointers 231 which are utilized when the ledger sheet does not have a previously printed line of data from which to measure but has ruled lines. Thus when the operator inserts a ledger sheet 63, if there is a previous posting thereon, it is aligned between lines 230, if posting is desired on the next following line. If posting is desired on some selected line not necessarily the next one, the ledger sheet is positioned so that pointers 231 are on the line above which posting is desired.

Frequently it is desired to post on each of a number of ledger sheets upon a line having the same location from the bottom of the sheet for all of them. In such case, alignment is effected by means of fixedly located stops 232 (Figs. 20 and 21) which are pivoted at 233 on an arm 234. This arm is clamped to the table 21 by thumb screw 235 in the desired position. Insertion of sheet 63 is effected by sliding it forwardly beneath stops 232 and then backing it against the stops which tilt to let the sheet pass. To remove the sheet the upper ends of the stops are depressed by the fingers of the operator to raise the stops out of engagement with the sheet.

Moistening device

It was stated above that the medium for applying the solvent to the area to be transferred comprises a ribbon. This ribbon indicated at 99 in Figs. 4 and 5 normally rests in a solvent reservoir comprising a channel member 100 integral with side members 101 and 102 which rest on and are removably secured to projections extending inwardly from the side frames 22 and 23. The ribbon 99 normally rests on a pad 103 resting on an angular plate 104. On the bottom of the channel 100 is a length of wick 105, the purpose of which is to maintain the fluid level of the solvent just high enough so that the lower corner

of the pad 103 is immersed therein. The solvent is supplied by an inverted container 106 provided with a spout 107 which is inserted into a receiver tube 108 so that the end of the spout 107 rests on the wick 105. When the machine is in operation, it rests with the table 21 at approximately the angle indicated in Fig. 4 in which position the level of the solvent is substantially as indicated by the dotted lines. The purpose 10 of the pad 105 on the bottom of the reservoir upon which the end of the tube 107 rests is to control the level of the solvent in the reservoir. If the end of the tube 107 rested on the bottom of the channel member 100, the level of the solvent would fall until the aperture of 107 was uncovered. Then a sudden rush of liquid would raise the level too high. By use of the pad 105, the liquid is absorbed from the supply 106 as it is used, maintaining the level constant.

20 The pad 103 (Fig. 4) comprises a length of wick next to the angular plate 104. On top of the wick is a plurality of thickness of blotting paper and finally on the blotting paper is a length of fabric having a vertical pile or nap. It has been found that this arrangement of materials provides the correct degree of moisture for the ribbon 99 and that the nap obviates the tendency of the ribbon to stick to the pad as is the case when a comparatively smooth fabric is used. The purpose 25 of the piled fabric 103 is to control the amount of solvent reaching the ribbon. Also, the pile permits the entire length of ribbon to leave the pad when it is moved to moistening position. If the pad 103 were provided with a flat surface of closely woven or fabricated material, the center portion of the ribbon would have a tendency to adhere when the ribbon is moved, and the snap of this portion of the ribbon would throw small drops of solvent on to the sheet 153 causing the carbon to run and resulting in a smudged copy.

The ribbon 99 is carried tightly stretched between arms 110 fast on a shaft 111 pivotally supported in the end plates 101 and 102. The ribbon, as previously stated, normally occupies a position in contact with the pad 103, it being pressed thereagainst by the weight of a cover 113 fast on a shaft 114 journaled in the plates 101 and 102. At the proper time the cover 113 is raised and the ribbon 99 is swung to the position in which it is indicated by dotted lines (Fig. 5). The mechanism for raising the cover 113 and operating the ribbon arms 110 will now be described.

55 Referring to Fig. 16, a cam 115 on the shaft 38 rocks an arm 116 on the shaft 75 counterclockwise against the tension of a spring 133 and by a connection 117 rocks a lever 118 clockwise. The lever 118 is secured on a shaft 112 whose one end has an arm 118a fast thereon (Fig. 3). The upper end of arm 118a cooperates with a stud 119 carried on the free end of an arm 120 fast on the cover shaft 114. The clockwise movement of the lever 118 rocks the arm 120 and the shaft 114 counterclockwise to raise the cover 113 from the position shown in Fig. 4 to the position shown in full lines in Fig. 5.

When the cover 113 is partly open, the lever 118a continuing its clockwise travel strikes the stud 121 on a gear 122 free on the shaft 114 rocking said sector counterclockwise against the tension of a spring 132. The sector 122 meshes with a gear 123 fast on the shaft 111, the gear 123 and shaft 111 being thus rotated clockwise to swing the ribbon arms 110 to the position indi-

cated by dotted lines (Fig. 5), in which position the ribbon 99 occupies a position in the downward path of a platen 124 mounted in the channeled lower edge of the pressure bar 83, just before said bar starts its downward movement.

Pressure bar

The pressure bar 83 is slidably vertically in grooves 126 in the side frames 22 and 23 (Figs. 1 and 5) and is operated by a pair of links 126, one being pivotally connected to the bar 83 near each end. The links 126 are connected at their lower ends to arms 127 fast on a shaft 128 (Fig. 2), one of said arms being disposed near each end of said shaft. An arm 127a (Fig. 2) is connected by a link 129 to one arm of a bell crank 130 pivoted on the shaft 128. A pair of cams 136 on the shaft 38 cooperates with antifriction rollers on the bell crank 130 to rock it first clockwise and then counterclockwise to normal. The clockwise movement of the follower through the link 129, arms 127 and links 126 lowers the pressure bar 83 to cause the transfer and the counterclockwise movement of said bell crank 130, through the same linkage, raises the pressure bar to normal position.

The shaft 112 at one end carries an arm 236 (Figs. 3 and 17) to which is connected a link 237 extending to a lever 238 which in turn is connected by a link 239 to an arm 240 on shaft 52. As shaft 113 is rocked clockwise to rotate the ribbon 99, a spring 241 will cause counterclockwise rocking of shaft 52 so that the fingers 51 thereon will be rocked out of the path of travel of the ribbon to the position shown in Fig. 5.

Paper feed—original

Referring to Figs. 4 and 5, a feed roll 137 is mounted on a shaft 138 journaled in the frames 22 and 23. A plurality of pressure rolls 139 each carried between a pair of arms 140 are pressed against the roll 137 by springs 141. The arms 140 are pivotally mounted on a shaft 142 supported in brackets secured to the cross bar 25.

Secured to one end of the shaft 138 is a ratchet wheel 144 (Fig. 14) with which cooperates a spring pressed feed pawl 145 carried on an arm 146 free on the shaft 138. A link 147 connects the arm 146 to an arm 148 pivotally supported on the frame 22. An antifriction roller 149 normally rests on the flattened end of an arm 150 secured to the shaft 88.

It will be remembered that the shaft 88 rocks first clockwise and then back to normal position under the influence of the cams 84, the arm 150 making a similar excursion (Fig. 3). When the arm 150 rocks clockwise from beneath the roller 149, a spring 151 draws the arm 148 and link 147 downwardly rocking the arm 146 clockwise to retract the pawl 145. After a transfer has been made, the cams 84 cause the arm 150 to rock counterclockwise to normal position, at which movement an inclined or cam surface 150a of the arm 150 moves the link 147 upwardly rocking the arm 146 counterclockwise to feed the original copy one line space. A spring pressed retainer 152 (Fig. 14) serves to hold the roll 137 and the original copy in alignment.

The original from which a transfer is to be made indicated at 153 (Figs. 4 and 5) is inserted over a shield 154 passing beneath the reservoir 100, between a bar 155 and a plate 156, between the feed roll 137 and the rolls 139 and over the arms 140. The shield 154 is mount-

ed on a rod 157 extending between the plates 101 and 102. The bar 155 is carried between two arms 159 (see also Fig. 2) pivoted on a shaft 160 supported in the brackets 143. A spring 161 holds the arms 159 and the bar 155 in the position in which they appear in full lines in Fig. 2. The plate 156 is secured to the shaft 160 and is normally held in the position in which it is shown in full lines in Fig. 4 by springs 162 attached to levers 163 which are also secured on the shaft 160.

In order to insert an original copy sheet, a pair of arms 164 (Fig. 4) is rocked counterclockwise. These arms are secured one on each end of a shaft 165 journaled in the brackets 143, and which shaft is provided with notches into which fit the arms 140. Upon counterclockwise movement of the arms 164 and shaft 165 the flattened portions of the shaft bearing 20 against the arms 140 rock these arms also counterclockwise to separate the rollers 139 from the feed roll 137. During this movement studs 166, one on each of the arms 140, contact the plate 156 and carry the latter therewith, the parts being shown in their moved positions in dotted outline in Fig. 4. This provides a free passage for the original sheet 153 between the bar 155 and plate 156 and between the feed roll 137 and the pressure rolls 139.

When the arms 164 are restored clockwise to their normal position, the springs 141 press the original sheet 153 tightly between the rolls 139 and the feed roll 137. The clockwise movement of the bar 155 is limited by the arms 159 striking collars on the shaft 138 (Fig. 2). Adjustable stop screws 167 are provided to limit the clockwise movement of the shaft 160 and plate 156 so that, as the parts appear in their normal position in Fig. 4, there is a slight clearance between the bar 155 and plate 156 to permit free movement of the original 153 when line spaced as above described.

It is important that the ribbon 99, the original copy 153 and the ledger sheet 63 do not come into physical contact until the instant pressure is applied by the pressure bar 83. The reason for this is that it is desired to produce a clean copy without smudges or smears which would occur if the sheet 153 touched sheet 63 during movement of either or, if the moistened ribbon 99 touched the original sheet 153 before pressure is applied, the solvent would cause the carbon deposit on the back of the original to run so that upon application of pressure a smudged copy would result.

In order to avoid this and produce a clean copy, these elements are brought into close proximity but not into actual contact just before pressure is applied and are quickly separated thereafter.

To accomplish this, the mechanism described above and illustrated in Fig. 16 does not move the ribbon 99 all the way to transfer position but moves the arms 110 which carry the ribbon to approximately the position indicated by dotted lines in Fig. 5, in which position the arms 110 lie in the paths of arms 168 (Fig. 7) pivotally mounted on the pressure bar 83. Also mounted on the pressure bar 83 are latch pawls 169 and stretched between arms 168 and pawls 169 are springs 170. Pins 171 on the pawls 169 extend beneath the plates 101 and 102 holding the pawls 169 disengaged from their associated arms 168 when the bar 83 is in its uppermost position (Fig. 6).

As the pressure bar 83 commences its downward movement, the pins 171 move away from the plates 101 and 102. During the continued downward movement of the bar 83, the arms 168 come into contact with the ribbon arms 110 and, since the springs 170 (Figs. 6 and 7) are of greater strength than the springs 132 (Fig. 16), the ribbon arms 110 are rocked further clockwise to the position shown in full lines in Fig. 5.

Referring to Fig. 7, the arms 159 which carry the guide bar 155 are provided with bent portions or ears 174 which extend into the path of travel of the ribbon arms 110. The ribbon arms 110 come into contact with these ears carrying the arms 159, the bar 155 and consequently the original sheet 153 downwardly from the position shown in Fig. 4 to that illustrated in full lines in Fig. 5. Just before pressure is applied by the platen 124, said platen, the ribbon 99, original 153 and the ledger sheet 63 occupy the positions in which they are shown in Fig. 5, where it can be seen that, while these members are close together, they are slightly separated. The pressure on the arms 159 also presses the bar 155 downwardly against the plate 156 to grip the original sheet 153, thus preventing displacement of this sheet.

The movement of the pressure bar 83 is continued downward to apply pressure and then upwardly to its normal position. As the bar continues downwardly from the position shown in Fig. 5, the arms 159 and ribbon arms 110 being stopped by the plate 21 the arms 168 rock to the position shown in Fig. 7, where the arm 168 is latched by arm 169. The purpose of thus latching the arms 168 in their moved position is to prevent the springs 170 from holding the ribbon arms 110 and the arms 159 down until the arms 168 strike studs 178, in other words, to permit a quick separation of the ribbon 99, original 153 and ledger sheet 63 upon commencement of the upward movement of the bar 83. This quick separation is necessary to prevent smudging and running of the carbon.

As the bar 83 nears the end of its upward stroke, the ears 171 of the pawls 169 strike the under sides of the plates 101 and 102 unlatching the arms 168 which assume their normal positions in readiness for another operation.

As soon as the pressure is released, the mechanism illustrated in Fig. 13 moves the ledger carriage to its original position and the cam 72 (Fig. 9) raises the bar 82 to release the grippers 65. The operator may now adjust the ledger sheet 63 to the next line or insert another sheet to the next unused line.

After the pressure bar 83 is restored, the cam 115 (Fig. 16) permits the arm 168 to rock counterclockwise under the influence of the spring 133, whereupon the spring 132 rocks the sector 122 clockwise rotating the gear 123 and shaft 111 counterclockwise to restore the ribbon 99 to its position on the pad 103 in the solvent reservoir 100. The pin 131 causes arm 120 to return to rock shaft 114 clockwise to close the cover 113.

Also near the end of the operation, the paper feed mechanism (Fig. 14) operates to feed the original sheet 153 one line space.

Referring to Fig. 4, the lever 163 extends downwardly below the plate or table 21 where it cooperates with levers 176 suitably mounted to rock on a suitable rod. The lever 163, as set forth above, is rocked counterclockwise upon operation of the arms 164 to release the rollers 139 for

the purpose of removing the old sheet 153 and inserting a new one. This movement of lever 163 rocks the levers 176, opening a pair of contacts 177 which are wired in series with the motor 28.

5 This opens the circuit to the motor to prevent operating the machine while inserting a new sheet.

The foregoing describes the operation of the machine substantially as in the patent referred to. The improvements of the present invention will now be set forth with particular reference to their relationship with the structure of the prior machine.

Original sheet feeding mechanism

It is to be noted that the original sheet 153 requires to be fed with considerable exactitude, so that a line of printed data is presented beneath the pressure bar for each operation of the feeding mechanism. Generally, the operator of the machine observes the movement of the original sheet, and by means of the usual vernier adjusting knob designated at 180 (Fig. 1) effects a slight rotation of the feed roll 137 in either direction with respect to its supporting shaft 138, if there has been any slight creep or slippage of the sheet with respect to the printing position. Where the original sheet employed is of the continuous perforated edge type, the mechanism about to be described will function to automatically and periodically adjust the sheet, so that the operator's attention in this respect is not required.

Referring to Figs. 1, 4, and 22, a pair of plates 181 are fastened one to each of the side frames 22 and 23. These two plates are spaced apart by a tie bar 182 and serve to support a shaft 183. Mounted on the shaft are two pin wheels 184 which are slidable along the shaft but through key and slot connection are arranged to rotate therewith. At one extremity of shaft 183 there is secured a gear 185 (Fig. 11) which meshes with a gear 186. The latter is pivoted at 187 on an arm 188 (see Fig. 22) which in turn is pivoted on a stud 189 carried by a side plate 181. On the stud 189 is a gear 190 meshing with gear 186 and also meshing with a gear 191 which is integral with the feed roll 137. The gears 191 and 185 are of the same diameter so they rotate with a 1:1 ratio. The arm 188 lies in the plane of the hub of gear 185 and the free end of the arm is normally spaced a slight distance away from the hub (Fig. 11) where it is held by the following mechanism.

55 As seen in Fig. 22, the arm 188 is integral with a shorter arm 192 which lies beneath a pin 193 and in an arm 194, which latter is normally urged clockwise as viewed in Fig. 12 by a spring 195. The pin 193 rides in a cam slot 196 of a member 197 which is secured to the shaft 165, to which the pressure roll release arm 164 is also secured. When the arm 164 is in position to permit the pressure rolls 139 to engage the feed roll 173, pin 193 is in the left hand end of slot 196, so that arm 194 is in its clockwise position as viewed in Fig. 12 and through arm 192 holds the arm 188 in its position of Fig. 11, away from the hub of gear 185. When shaft 165 is rocked clockwise, roller 193 rides outwardly into the concentric portion of cam slot 196, causing pin 193 to rock away from the arm 192 and causing spring 195 to rock arm 188 against the hub of gear 185, carrying gear 186 with it. This slight movement causes gear 185 to advance slightly ahead of the feed roll gear 191.

Referring to Fig. 4, the original sheet is passed beneath the feed roller 137 as usual and then over the pin wheels 184 as shown. To do this arm 198 freely pivoted on shaft 199 is rocked clockwise carrying with it retaining plates 200 (Fig. 1) which are slidably positionable along the shaft 199 and which serve to hold the sheet in position on the pin wheels. With the pressure rolls 139 against the feed roll, the latter will advance the sheet in the usual manner and the pin wheels 184 will rotate therewith, with the pins moving idly in the perforations of the sheet. Once each revolution of feed roll 137 or specifically after eleven spacing operations (there being eleven teeth in the ratchet wheel 144, Fig. 14), the pressure rolls 139 are moved away from the feed roller 137 by partial rotation of shaft 165 which, as has just been pointed out, also effects slight additional rotation of the pin wheels 184. With the sheet so freed, this slight additional rotation of the pin wheels will cause the pins to engage the leading edges of the perforations and, where there has been any slight slippage within the last eleven operations, the pins will advance the sheet a slight extent. Thereafter, the pressure rollers 139 reengage the feed roll for another eleven operations when the pin wheels again act to take up any slippage. Thus, there is a periodic and automatic alignment of the original sheet through the rocking of the shaft 165.

The manner in which shaft 165 is periodically rocked may best be explained in connection with Figs. 10 and 22 wherein there is shown an arm 201 freely carried on shaft 165 and having an adjustable screw 202 which abuts an extension 203 of the arm 164. Connected to arm 201 is a link 204 whose lower end is provided with a hook 205 which is urged toward the left by a spring 206. The upper end of link 204 terminates in a finger 207 which is arranged to cooperate with an axially adjustable stop collar 208 which is threaded on a stud 209 in one of the plates 181. The stop collar is manually set by rotating it on the threaded stud 209, so that it occupies either of two positions, one in which the collar lies in the plane of finger 207 and the other in which the collar is in its left hand position, out of the plane of the finger. With the collar in its left hand position, finger 207 is free to move toward the stud 209.

On the feed roller shaft 138 and in the plane of link 204 is a notched disk 210 which during its advance will have its notch in line with a projection 211 of the link, so that the latter is free to rock clockwise under the influence of spring 206. The hooked end of the link lies in the plane of a pin 212 carried by an arm 213 secured to the shaft 128 which, as explained, is rocked counterclockwise to bring the pressure bar downward against the sheet. During such movement, the pin 212 swings counterclockwise and will engage the hook 205 so that, on the upward stroke of the pressure bar, the pin will draw link 204 downwardly rocking arm 201 counterclockwise thus effecting the rotation of shaft 165 necessary to produce the aligning action of the pin wheels. At the extremity of the downward stroke 204, an adjustable pin 214 therein will engage the hub of arm 213 to disconnect the hook 205 from pin 212 and spring 206 will return the parts to their initial position.

It is to be noted that shaft 165 is not rocked its full extent under the automatic operation just described but just enough to lift pin 193

(Fig. 12) into the concentric part of slot 196. The pressure rolls 139 (Fig. 4) are accordingly but slightly removed from roller 137 and the pins 166 rock plate 156 to rotate shaft 160 upon which lever 163 is secured. The ultimate movement of lever 163 is not sufficient to open contacts 171 under these circumstances.

Where perforated sheets are not employed, the action of link 204 may be disabled by setting the stop collar 208 in its right hand position, where it will engage finger 207 and hold it in such position that the projection 211 will not drop into the notched disk 210. As a further alternative where perforated sheets are employed, the arm 164 may be manually rocked to the pressure roller releasing position shown in dotted outline in Fig. 10, and maintained there by an extension 215 on the collar 208. This has the effect of holding the pressure rolls 139 out of engagement with the feed roll 137, so that advance of the sheet is solely through the action of the pin wheels 184.

The pin wheels are axially slidable along shaft 163 by means of forked arms 216 which are pivoted on the shaft 199 and held in position by thumb screws 217. When a sheet is first inserted, the pin wheels are spaced apart so that they are aligned with the perforated edges and engage the holes. The thumb screws are then turned down to hold the parts in such position. Thereafter, an internally threaded knob 218 mounted on plate 181 for rotation therein but constrained against axial movement may be rotated. This knob is threaded on the extremity of shaft 199 and will thus move the shaft slightly in either direction, to move the pin wheels and the sheet to a position of exact alignment with respect to the ledger upon which posting is to be effected.

Repeat key operation

Referring to Fig. 14, a repeat key 219 is provided which is horizontally slidable on a pin 220 and has a notch 221 which drops over a shoulder 222 when the key is pressed inwardly, to hold the key in such position, a spring 223 serving to hold the key in a slightly rocked position with the right edge of the notch 221 engaging shoulder 222. In such position the inner end 224 of the key will lie in the path of an extension 225 of the arm 146, so that when the machine is operated the arm is prevented from rocking effectively. A slight rocking, however, is permitted during which the spring pressed pawl 226 moves to a position above the extension 224, so that on the return movement of arm 146 pawl 226 will engage and degress the extension 224, causing the key to rock about pin 220 and disengage notch 221 from pin 222. The spring 227 will thereupon return the key to its normal position. This repeat key is pressed before a line is to be posted, so that the master or original sheet is not advanced during the posting operation but remains for second posting. During the second posting, however, feeding will be effected. Should a third posting be required from any line of the master sheet, the key is pressed a second time just prior to making the second posting.

A device shown in Figs. 18 and 19 is provided to indicate on the lines of the original sheet which lines have been posted. This device comprises a capped cylinder 250 from which a tube 251 extends downwardly beside the pressure bar 83. The cylinder contains a marking fluid which passes down through the tube by means of a suitable wick. The cylinder is secured to

one end of a leaf spring 252 whose other end is fastened to a guide 253 which may be positioned along a slide 254 and secured as by a thumb screw 255. When the pressure bar 83 descends, the lower end of tube 251 will touch the sheet 153 and make a mark thereon, as indicated at 256 (Fig. 20), spring 252 flexing when the tube strikes the paper. As noted in Fig. 20, the mark 256 is made just above the line posted from.

When the repeat key is operated it moves a link 257, connected thereto into a position where a cam portion 258 thereof lies in the path of a lever 259 pivoted to the pressure bar. Thus, when the pressure bar descends for the first of two postings, lever 259 will be rocked by cam 258 and will move slide 254 to the left as viewed in Fig. 18, carrying with it the marking cylinder 250 and tube 251, so that the mark made will be to the left of its normal location. Upon return of the bar 83, spring 260 restores the parts to the position of Fig. 18, so that during the second posting stroke (key 219 having been restored as explained) the mark will be made in its normal position, resulting in two marks appearing side by side as indicated in Fig. 20, to denote that the related line was posted twice.

Referring to Figs. 1 and 6, there are provided two pressure adjusting knobs 261 above the pressure bar 83 which serve to adjust and equalize the pressure applied. These knobs are threaded to shouldered pins 262 whose lower ends are pivoted to the actuating arms 126. Thus the pins 262 make an excursion with arms 126 of invariable extent. By turning the knobs 261, pins 262 and the pressure bar 83 are relatively shifted, springs 263 serving to urge them apart. Thus, when thick ledger sheets are to be used, the bar 83 is moved and when thinner sheets are used, the bar is adjusted downwardly. To indicate the relative adjustment of the parts, pointers 264 are provided, one at each end of bar 83. Each pointer is pivoted at 265 to bar 83 and has a short arm 266 resting on a shoulder of pin 262 against which it is held by a spring 267. A scale 268 indicates the relative displacement of bar 83 and pin 262, and with the scale reading the same for both ends of the bar, the operator knows that the pressure will be uniform along the length of the bar.

To prevent operation of the release bar 49 (Fig. 1) there is provided a lever 270, positioned as shown in Fig. 1, which is pivoted at 271 (Fig. 15) and has a depending arm 272. Arm 272 connects with a slide 273 which normally lies in the path of arm 62 (see Fig. 8) so that operation of bar 49 and lever 62 is prevented. When a ledger sheet is placed in position it rocks lever 270 counterclockwise (Fig. 15) and withdraws slide 273, so as to free lever 62 for operation. A bell crank 274 pivoted at 275 has one arm engaging a pin 276 in arm 272 and the other arm underlying bar 82 so that when bar 82 is moved down to permit the clamps 65 to grip the ledger sheet, bell crank 274 is rocked and in turn it rocks lever 270 away from the ledger sheet so as to not interfere with its movement into posting position.

Frequently there may be some data on the original sheet 153 which it is not desired to transfer to or post upon the ledger sheet. For this purpose, a resilient shield 280 (Figs. 23 and 24) is provided which may be slid upon bar 55 as shown and held in position by a spring clip 281. When in position as shown, the shield is interposed between the pressure bar 83 and sheet 153.

on one side and the ledger sheet 63 on the other side so that when the bar descends the sheet 153 will not contact sheet 63 at the place where shield 280 is located.

5 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

15 What is claimed is:

1. In a machine of the class described having an original sheet to be transferred, a table to support a copy sheet, a pressure bar to press the original sheet and copy sheet together, said bar being repeatedly operable, in combination with feed rollers normally engaging said original sheet to line space the same for each operation of the pressure bar, an aligning device for engaging the original sheet and adjusting the same to bring the lines thereon into a right angle relationship with the direction of feeding, said device being normally ineffective, and means called into action periodically for disengaging the feed rollers from the original sheet and rendering the aligning device effective.

20 2. In a machine of the class described having a sheet to be advanced past a fixed position line by line and an impression member operable repeatedly, once for each line presented to the fixed position, in combination with a feed roller frictionally engaging said sheet to line space the same for each operation of the impression member, a pin wheel geared to said feed roller and having its pins coating idly in perforations in 25 said sheet, and means controlled by said feed roller for causing the roller to be ineffective to feed the sheet, said pin wheel thereupon effectively engaging the sheet for feeding thereby.

25 3. In a machine of the class described having a sheet to be advanced past a fixed position line by line and an impression member operable repeatedly, once for each line presented to the fixed position, in combination with a feed roller frictionally engaging said sheet to line space the

30 same for each operation of the impression member, a pin wheel geared to said feed roller and having its pins coating idly in perforations in said sheet, means for causing the pin wheel to oscillate, and means operative after a predetermined number of line space operations for freeing the sheet from feeding engagement with the roller and rendering the pin wheel oscillating means effective whereby the pin wheel will engage the leading edges of the holes in the sheet and move the same.

35 4. In a machine of the class described having a sheet to be advanced past a fixed position line by line and an impression member operable repeatedly, once for each line presented to the fixed position, in combination with feeding means normally engaging the sheet to line space the same for each operation of the impression member, a second feeding means adjacent to the first feeding means and idly engaging the sheet, driving means therefor, and means automatically effective after a predetermined number of line space operations for rendering the first named feeding means ineffective and concomitantly rendering the second feeding means effective.

40 5. The invention set forth in claim 4, in which

the second feeding means is effective only during the interval after the predetermined number of line spacing operations and before the next following line space operation.

6. The invention set forth in claim 4 in which manually positionable means is provided and means controlled thereby when in one position, rendering the second feeding means ineffective, when in another position rendering the first feeding means ineffective and when in a third position rendering both feeding means effective.

7. In a machine of the class described having a sheet to be advanced past a fixed position line by line and an impression member operable repeatedly, once for each line presented to the fixed position, in combination with a feed roller, line spacing mechanism therefor, a pressure roller normally pressing the sheet against the feed roller for advance thereby, a manually operable release lever for disengaging the pressure roller from the feed roller and means operable after a predetermined number of line spacing operations for automatically operating said release lever to momentarily release the sheet.

8. In a machine of the class described having a sheet to be advanced past a fixed position line by line and an impression member operable repeatedly, once for each line presented to the fixed position, in combination with a feed roller, line spacing mechanism therefor, a pressure roller normally pressing the sheet against the feed roller for advance thereby, a manually operable release lever for disengaging the pressure roller from the feed roller, a cam connected to the feed roller and means controlled by said cam upon each revolution of the feed roller for causing an operation of said release lever to momentarily release the sheet.

9. The invention set forth in claim 8 in which timing means is provided and coordinated with the line spacing to cause said momentary operation of the release lever to occur during the interval between two successive spacing operations.

10. In a machine of the class described, a pair of pin wheels, a driving shaft therefor, said wheels being slidable on the shaft for alignment with hole columns in a record to be advanced, fingers for sliding the wheels along the shaft, a rod supporting said fingers, means for clamping the fingers to the rod after the wheels are positioned, and means for moving the rod either way in the direction of its axis to concurrently slide both wheels along the shaft.

11. In a machine of the class described having a table, a pressure bar, an original transfer sheet, a copy sheet being positionable in superposed relationship between said bar and table for transfer of a line of data from the trans-

fer sheet to the copy sheet, in combination with a supporting bar connected to the table, a shield positionable along said supporting bar and extending between said sheets beneath the pressure bar to prevent transfer of data from a selected part of the transfer sheet.

12. In a machine of the class described, a table, a pressure bar, a transfer sheet positioned between the bar and table, a copy sheet being positionable beneath the transfer sheet to receive copy upon operation of the pressure bar, power means to operate the bar, a key lever operable to render the power means effective, said lever being normally locked against operation and means controlled by a copy sheet when one is placed in copying position for causing unlocking of said key lever whereby said pressure bar is operable only when a copy sheet is in position.

13. In a machine of the class described having a table, a pressure bar, an original transfer sheet, a copy sheet being positionable in superposed relationship between said bar and table for transfer of a line of data from the transfer sheet to the copy sheet, means for operating the pressure bar, line spacing mechanism for advancing the original sheet after each transfer operation, a marking device effective upon each transfer operation to make a mark on the original sheet adjacent to the transferred line in combination with, a repeat key, means controlled thereby for preventing operation of the line spacing mechanism upon the first operation of the bar following actuation of the repeat key, so that a second operation of the bar will repeat the transfer of the same line of data, and further means controlled by said key for causing the marking device to make two spaced marks adjacent to the transferred line of data.

14. In a machine of the class described, the combination of an original sheet containing material to be copied, a table to support a copy sheet, index fingers wherewith the original sheet may be adjusted in columnar relationship with the copy sheet to select a column to receive the transfer, a positionable stop attached to said table against which stop the edge of the copy sheet is placed, said stop being located with respect to the index fingers to select a predetermined position on the copy sheet, said stop being manually tiltable out of the plane of the copy sheet to enable the sheet to be readily removed by sliding in the direction of the stop after a copy has been effected, and means to automatically move the copy sheet from said stop to position to receive the copy.

ALBERT W. MILLS.
